CLAIM

I claim the ornamental design for an ophthalmic occluder, as shown and described.

DESCRIPTION

FIG. 1 is a front elevational view of the ophthalmic occluder of my design, the rear elevational view being a mirror image;

FIG. 2 is a bottom plan view thereof;

FIG. 3 is a top plan view thereof;

FIG. 4 is a left side elevational view thereof; and,
FIG. 5 is a right side elevational view thereof.
